UNITED STATES PATENT OFFICE.

CHARLES F. STREIT, OF CINCINNATI, OHIO.

SOFA-BED.

SPECIFICATION forming part of Letters Patent No. 585,366, dated June 29, 1897.

Application filed December 29, 1894. Serial No. 533,246. (No model.)

To all whom it may concern:

Be it known that I, CHARLES F. STREIT, a citizen of the United States, and a resident of Cincinnati, in the county of Hamilton and State of Ohio, have invented certain new and useful Improvements in Sofa-Beds, of which the following is a specification.

My invention relates to sofa-beds, and particularly to that class in which the back of the sofa is adapted to fold out to a horizontal position to form a double bed.

The object of the invention is to provide means by which the back is automatically locked in the upright position when thrown to place and the back-supporting frame thrown to the vertical position when the back is folded down to form the bed.

The invention will be understood from the following description of the accompanying drawings, in which—

Figure 1 is a transverse central section of the framework with the back in the upright position, the upholstering being indicated by dotted line, and the back and its support when thrown to the horizontal position as also shown in dotted line. Fig. 2 is a rear elevation of one end of the frame, the back being in the upright position, as when used for a sofa.

The seat-frame A and back-frame B are rectangular boxes of ordinary construction, each having end uprights A' and B', which are united together by hinges a. The arms C have socket-pins projecting from their under side to enter sockets in the rails A' and B', as shown in dotted line, Fig. 1. The purpose of making the arms detachable is to lift either one or the other out of the position it occupies when used as a sofa and place it alongside of its opposite member upon either one of the end rails B' when the back is thrown down to form a bed, the arms then forming the head of the bed and retaining the pillows in position. By this means either end of the bed may be used as the head or foot, as desired.

Upon the back of frame B are metal bearings b, which have pins projecting from them into metal plates b', which are secured to the ends of the back leg-frame B². D is a metal link the lower end of which is pivoted upon the extended end a' of a bar or base of the

stationary frame A, and the upper end is pivoted to the edge of the leg b² above its lower end. The link D is curved, as shown at d, to pass under the edge of the back when in the upright position, as shown in Fig. 1, and has formed integral with it a rib d', which rib is for the purpose of giving weight to the curved portion, so as to throw it inward toward the stationary part of the lounge when the weight is brought past the vertical line of its lower pivot. It is understood, of course, that one of these links is employed at each end of the frame, both being connected to the extension of the stationary frame and the supporting-legs b². The link and legs act as a toggle-jointed lever when the frame is thrown to the upright position, and it is evident that any pressure against the back of the sofa only forces the jointed ends of the lever members more firmly against the framework of the back and holds the back rigidly in position.

To throw the back down, it is necessary to take hold of the frame B² or one of the legs b² and draw the jointed ends outward until they are a short distance away from the back, when the back may be let down to the position shown in dotted line, Fig. 1, in which position the link D supports the frame B² and legs b² in a vertical position underneath the back and supports the back in a horizontal position. The sofa is again formed by simply lifting the back up to the position shown in Fig. 1, when the weighted portion d' of the link D will throw the leg b² firmly against the lower longitudinal rail of the back and lock the parts rigidly together.

The design of the frames and upholstering may be varied without varying the principle of the invention, and the parts may also be varied in minor mechanical features.

Hence, without limiting myself to the specific details of construction shown, what I claim as new, and desire to secure by Letters Patent, is—

1. The stationary frame having rearward extensions at each end and having its straight arm thrown against the lower rail of the back when the back is thrown to a vertical position to lock the parts rigidly together, the back-frame hinged at its upper edge to the upper edge of the stationary frame, the back-

supporting leg-frame pivoted to the rear of the back-frame near its top, and the inwardly-curved links pivoted to the rear extensions of the stationary frame and to the back-supporting legs near their lower ends, substantially as shown and described.

2. The combination of the stationary frame having rearward extensions upon its back at each end, the back-frame hinged at its top to the top of the stationary frame, the leg-frame pivoted near its top to the top of the back-frame, the inwardly-curved link pivoted to the rearward extensions and the back-supporting legs near their lower ends, the curved

portion of said link having a weight formed integral with it to throw the curved portion of said link under the lower edge of the back-frame when elevated to hold the lower end of the legs firmly against the lower edge of said back-frame, firmly brace the said back-frame in its upright position and prevent accidental falling of said back-frame, substantially as shown and described.

CHARLES F. STREIT.
